UNITED STATES PATENT OFFICE

WILLIAM D. McCLELLAN, OF LAUREL, MISSISSIPPI

CAR RERAILER

Application filed May 28, 1930. Serial No. 456,699.

This invention relates to car rerailers, the primary object of the invention being to provide a device of this character which will elevate and guide the truck wheels over the track, novel means being provided for preventing slipping or lateral movement of the car wheels over the rerailer.

Another object of the invention is to provide a rerailer of this character having means to secure the same against lateral movement with respect to the ties on which the same are positioned, thereby insuring against the wheels of the truck operating to force the rerailer away from the rail.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

25 Referring to the drawings:

Figure 1 is a perspective view of rerailers constructed in accordance with the invention.

Figure 2 is a plan view thereof.

30 Figure 3 is an end elevational view of the rerailer.

Referring to the drawings in detail, the rerailers embodying the present invention include an inner plate 5 and an outer plate 6, the plates being so constructed that they will fit over the rails of a railway track to be engaged by the wheels of the truck to be replaced on the rails. The plate 5 is preferably of rectangular formation, the upper surface thereof being inclined upwardly from the ends thereof towards the center of the plate, the central portion of the plate being of a thickness so that the upper surface thereof will lie flush with the tread of the rail on which it is positioned.

45 Formed on the upper surface of the plate 5 are a plurality of curved ribs 7 spaced apart providing guideways therebetween, the ribs being curved towards the upper surface of the plate and towards the rail with which

the plate is associated, so that a wheel resting on a rib will be guided to the rail.

These ribs 7 extend from both ends of the plate, as clearly shown by the drawings. The reference character 8 designates a flange that extends from one edge of the plate, the flange being constructed to fit over the rail so that the wheels of a truck in passing from the ribs will strike the inner edge of the flange 8 and be guided to the rail, it being understood that the flange 8 extends slightly above the upper surface of the plate 5 to present a contacting edge for the wheels. Extending downwardly from the plate 5, are spikes 9, the spikes being arranged in spaced relation with each other, so that regardless of where the plate is positioned, certain of the spikes will pass into the ties on which the rerailer is positioned.

The rerailer section 6, which is used on the outside of a rail of a track, is substantially the same as the rerailer section 5 and embodies a plurality of spaced ribs 10 that extend from the ends of the plate 6, to a point adjacent to the center of the plate, the ribs being curved slightly towards the tread of the rail to guide wheels to the inner central edge of the plate.

This section or plate 6 is formed with a smooth upper surface 11, so that the flanges of the wheels passing over the rerailer section, may move directly over the upper surface of the section where they will drop onto the rail of the track disposed directly thereunder.

Spikes 12 extend downwardly from this section and are arranged along the side and ends of the plate, to be embedded in the ties on which the plate is positioned.

As clearly shown, the ribs of the rerailer sections taper from the bottoms thereof to the upper edges, presenting inclined surfaces to act as cams to move the wheels of the truck laterally, and prevent them from riding over the upper surfaces of the ribs.

Spikes such as indicated at 13 may be employed to further anchor the rerailer sections to the ties, when the rerailer sections are employed in rerailing exceptionally heavy rolling stock.

I claim:

1. A rerailer comprising rerailer sections, each of said sections including a rectangular plate, the upper surface of the plate being inclined upwardly from the ends thereof to a point intermediate the ends, curved ribs formed integral with the upper surfaces of the sections, said ribs being curved towards the rails on which the sections are positioned, lifts formed on the sections and overlying the rails with which the device is used, and spikes extending downwardly from the plates, said spikes adapted to embed themselves in the ties on which the rerailer rests.
- 15 2. A rerailer comprising rerailer sections, each of said sections embodying a rectangular plate, ribs on the upper surfaces of the plates, said ribs being curved from the ends of the sections towards the rails on which the sections are positioned, said ribs being tapered towards the upper edges thereof, and spikes extending from the bottoms of the plates to be embedded in the ties on which the sections are positioned.
- 25 3. A rerailer comprising rerailer sections, each of the sections embodying a plate, the upper surfaces of the plates being inclined from the ends towards the centers thereof, spaced ribs extending from the ends of the plates and terminating at points adjacent to the centers of the plates, said ribs being curved towards the rails on which the sections are positioned, and spikes extending downwardly from the plates to be embedded in ties on which the rerailer sections are positioned.

In testimony that I claim the foregoing as my own, I have hereto affixed my signature.

WILLIAM D. McCLELLAN.
